UNITED STATES PATENT OFFICE

WILLIAM T. KNOWLES, OF EVERETT, WASHINGTON

ONE-PIECE BINDER AND CAR STAKE

Application filed October 1, 1929. Serial No. 396,463.

The loading of poles and timbers upon railroad flat cars for transportation, especially poles of length greater than can be carried upon a single flat car, has been always a source of considerable annoyance and no little danger. Flat cars are provided, ordinarily, with sockets at each side, into which are customarily fitted stakes of stout timber to retain the load, and to strengthen the upper ends of the stakes they are ordinarily bound across and through the load, with light cables or strong wires. This serves, also, to hold the load more firmly in place.

Such timbers frequently break, permitting the load to roll off the side of the car, or to become so loose that the train must be stopped until the car or cars are reloaded, causing delay and inconvenience, and should the load be lost from the car there is grave danger of damage to the train itself, or to adjacent objects or persons.

For safety's sake, it has been customary to employ two such stakes, at least, adjacent each end of a load of poles, but especially where these poles are of such length that they must be loaded upon two connected cars the employment of two stakes has added a further problem, that of pivoting the poles in going about curves. The pivoting of the poles relative to the two stakes serves to wrench one or the other of the stakes from its socket, or to break it, thus leaving the load depending solely upon one stake, as before. Furthermore, since these stakes can be secured only in the sockets provided at the side of the car deck, and since it is not practicable to provide sockets inside of the margin of the car deck, the overhang of long poles resting upon two cars presents a further danger, that the middle portions of these poles will side-swi-pe objects as the train passes about sharp curves. The result has been that the transportation of such poles, and their loading, is more expensive than is economically desirable.

My invention, then, is concerned with means for securing such loads on flat cars, with ease and rapidity, with certain safety, and in such manner as to eliminate danger of breakage of stakes, and of side-swiping in passing about curves, and among the objects

of my invention, in addition to those already stated, are to make such load-securing means cheaply and conveniently, and preferably from otherwise waste products, or products of slight value, such as used railroad rails.

Among other objects relating to details of my invention are to provide extension means to permit higher piling of the load than would be normally permitted by the main load binder and stake, or other styles of stakes, to provide means for cross binding of the load, and to provide simple means for insuring that the load binder and stake will properly retain its position upon the car, or upon the bunks which may be employed to elevate it and the load above the car deck.

My invention comprises the novel load binder and stake, the novel association thereof with a car and with a timber bunk, and in general the novel load-securing means for cars, as shown in the accompanying drawings, described in the specification, and as will be more particularly pointed out in the claims which terminate the same.

In the accompanying drawings I have shown my invention in a preferred form, together with a modified form, and in association with conventional cars and bunks.

Figure 1 is a general side elevation of parts of three cars in a train, showing the manner of supporting such a load as long poles thereupon, by means of my invention.

Figure 2 is an end view of a car deck, with my invention secured thereupon, and shown in position to retain a load.

Figure 3 is a side elevation of my invention in place and in operation, a part being broken away.

Figure 4 is a section transversely through my load binder and stake, and associated parts of the bunk and load-supporting timbers.

Figure 5 is a detail section through one side of my device, illustrating the means for securing the same upon a car.

Figures 6 and 7 are views of one corner of a slightly modified form of my invention, showing the manner of manufacturing the same.

In and of themselves the railroad cars form

no part of my invention, and any type of flat car may be used. For clearness of illustration, the flat car is shown in Figure 1 as comprising the sills 10, the trucks 11, couplings 12, deck 1, and stake sockets 13 at either side. The latter have no purpose whatever in association with my invention.

It may be assumed that the poles P which constitute the load are of greater length than can be loaded upon one such flat car, though my invention will be of utility also when the poles or timbers are of such length as may be loaded upon a single flat car. In the latter case, two of my load-securing means would be employed, one at each end of the car, but as illustrated there is one only provided upon each of two adjoining connected cars. This load securing means consists of a rigid U-shaped frame, the uprights 2 being connected at their lower ends by the cross member 20. I prefer that these frames 2, 20 be formed of heavy metal bars or steel sections, and as used or worn railroad rails are available in considerable quantities, I prefer that these frames be made by bending a railroad rail at two points, as indicated at 21 (see Figure 2), which are spaced less than the width of the car deck, thereby providing the uprights 2 and the connecting bottom bar 20 all in one piece. The bending, in such case, would be in the plane of the web of the rail, and preferably with its flanges 22 outermost. The heavy heads 23 then serve to engage the poles P, at least at their sides, and serve as single points or edges about which the poles may pivot in going about curves, without cutting into the poles.

The flanges 22 offer a means by which the U-shaped frame thus formed may be secured upon the car, and while it may be secured directly to the car deck 1, I prefer to employ timber bunks, as indicated at 3, which are suitably secured transversely of the car deck, as by the spikes 31, and to these transversely extending bunks 3 the bottom bar 20 of the U-shaped frame may be spiked, as indicated by the spikes 24. To insure that the frames will not move transversely, relative to the bunk and car, the bottom web may be notched or otherwise cut out, as indicated at 25, and the spikes 24 will be received in these notches, thus effectively preventing sidewise movement of the frame.

Since there would be some tendency for the head of the bottom bar 20 of the frame to cut into the poles, with a considerable load above them, I may secure in place timbers 35 upon the top of the bunk 3, or at all events reaching above the top surface of the rail forming the cross bar 20 of the frame, as may be seen in Figure 4. These timbers 35 would be ordinarily secured to the bunk 3 by some such means as the spikes 36. These timbers carry the weight of the load.

Since it is desirable that the load be se-

cured by binding through from one side to the other, I may pierce the web in the uprights 2 of the frame at intervals, and as is indicated at 26, and through these holes may be passed or secured cables or wires 4, which bind the load together. It must be kept in mind, however, that the rigidity and stiffness of the frame described is sufficient to retain the load without such binding. However, for additional binding of the load together, I may employ stakes 5, one at either side of the load, connected through by binding wires 50. These stakes, it will be observed, are wholly free, and supported solely from the load itself, and are not connected to the car. They may be placed at intervals along the length of the load, wherever required, and binding wires 40 may extend entirely about the load at intervals, as, for instance, at the ends.

To enable loads to be piled higher than the normal capacity of the U-shaped frame heretofore described, I may provide extension bars 6, which lie between the head 23 and the bottom flange 20 of the rail, and adjacent the web of the uprights 2. These extension bars 6 may be perforated at intervals, as indicated at 60, and corresponding holes may be provided in the web of the frame members 2, at their upper ends, so that a single bolt 61, passed through the web and through the holes 60 in the bar 6, will effectively support these extension bars projecting above the ends of the frame. Additional bolts may, of course, be employed, and the holes 60 may be employed for the securing of additional binder wires 4.

Instead of bending the rail, as indicated at 21, the frame may be formed by cutting a notch from the upper portion of the rail, as indicated at 29 in Figure 6. The rail may be then bent reasonably sharply upon its bottom flange 22, and the edges of the notch 29 joined by welding, as indicated at 28 in Figure 7. The several parts might, in fact, be formed separately, and rigidly secured together; but I prefer that they be formed integral, and preferably bent, as indicated in connection with Figure 2 and others.

What I claim as my invention is:

1. In combination with a flat-car, a load binder and stake extending transversely thereof and comprising a rigid U-shaped frame, the uprights being disposed inwardly of the side edges of the car deck, and means for securing the cross member of said frame to the car.

2. A load binder and stake for the purpose specified, comprising a webbed and flanged metal bar formed in U-shape, with the web lying in the plane of the frame thus formed, and extension bars lying between the flanges and against the webs at the upper ends of the upright arms, and a bolt passing

through said extension bars and webs to secure the former in an adjusted position.

5 3. Load-securing means for flat cars comprising, in combination with two connected flat cars, a load binder and stake for holding poles upon flat-cars, comprising a rigid U-shaped frame secured transversely upon each car, said frame being bent at two points spaced by less than the width of the car deck
10 to which it is to be secured, whereby the poles, midway between the frames, will remain substantially within the confines of the cars in passing about curves.

15 4. In combination with a timber bunk, a load binder and stake comprising a railroad rail bent with its bottom flanges outermost at two spaced points to form a U-shaped frame, and spikes securing the web of the bottom portion of said frame to said bunk.

20 5. In combination with a timber bunk adapted to be secured upon a flat-car deck, a load binder and stake comprising a railroad rail bent at two spaced points with its bottom flanges outermost to form a U-shaped
25 frame, the bottom flanges in the cross member of said frame being notched at intervals, and spikes received in said notches and securing the frame to said bunk.

30 Signed at Everett, Washington, this 23rd day of September, 1929.
